(57) **CLAIM**

The ornamental design for a tray, as shown and described.

DESCRIPTION

FIG. 1 is a top, left side perspective view of a first embodiment of a tray showing the new design;

FIG. 2 is a front side elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, left side perspective view of a second embodiment of the tray shown in FIGS. 1-7 with indicia displayed on the front side of the tray, wherein said indicia is cut away from front side; and,

FIG. 9 is a top, left side perspective view of a third embodiment of the tray shown in FIGS. 1-7 with indicia displayed on the front side of the tray, wherein said indicia is raised from front side.

The broken lines shown in FIG. 7 depict portions of the tray that form no part of the claimed design.

1 Claim, 9 Drawing Sheets
